UNITED STATES PATENT OFFICE.

LEON C. SCHONEMAN, OF NEW YORK, N. Y.

DESIGN FOR A CLIP.

SPECIFICATION forming part of Design No. 34,398, dated April 23, 1901.

Application filed March 6, 1901. Serial No. 50,144. Term of patent 7 years.

To all whom it may concern:

Be it known that I, LEON C. SCHONEMAN, a citizen of the United States, residing at New York, in the borough of Manhattan and State of New York, have invented and produced a new and original Design for Clips; and I do hereby declare the following to be a full, clear, and exact description of the invention, such as will enable others skilled in the art to which it appertains to make and use the same.

My invention relates to improvements in wire clips used for fastening receptacles to the edges of bath-tubs, bowls, &c.

In the accompanying drawings, Figure 1 is a perspective view of my improved clip, and Fig. 2 is a plan view of the same.

The clip is made of wire, and it is composed of a horizontal portion *a*, bent at substantially right angles at *b* and *c*, having upright portions *d* and *e*, being again bent at substantially right angles at *f* and *g*, having horizontal portions *i* and *h*, said portions being arranged, however, at right angles to the portion *a*, said parts *i* and *h* being again bent at substantially right angles at the points *j* and *k*, the parts *l* and *m* extending downwardly from said angles, and substantially parallel

to the parts *d* and *e*, but of greater length. At the points *p* and *q* the parts *l* and *m* are again bent at substantially right angles, and the end portions *n* and *o* extend from the angles *p* and *q* forward toward the portion *a*, but diverging from each other and extending upward slightly. Roughly speaking, the parts *n* and *o* resemble a pair of horns. The parts *n* and *o* are adapted to bear against the outside of the tub or bowl, and to the portion *a* is attached a receptacle for soap or disinfectants. Pressure on the bowl is caused by the resilience of the clip, which acts to clamp the bowl between the portions *n* and *o* and the part *a*.

Having thus described my invention, what I claim as new, and desire to secure by Letters Patent of the United States, is—

The design for a clip as herein described and shown.

In testimony whereof I affix my signature in presence of two witnesses.

LEON C. SCHONEMAN.
